(57) **CLAIM**

The ornamental design for a cockpit seat tracks, as shown and described.

DESCRIPTION

Pursuant to 35 U.S.C. § 119(e), this application claims priority to U.S. patent application Ser. No. 13/360,461, filed Jan. 7, 2012, still pending entitled “Vehicle Crewstation Seat Assembly”.

FIG. 1 is a perspective view of the cockpit seat tracks with pilot seat shown;

FIG. 2 is a perspective view of the cockpit seat tracks in a retracted position;

FIG. 3 is a perspective view of the cockpit seat tracks in a stowed position;

FIG. 4 is a front isometric view of the cockpit seat tracks in the stowed position;

FIG. 5 is a rear isometric view of the cockpit seat tracks in the stowed position;

FIG. 6 is a left side isometric view of the cockpit seat tracks in the stowed position;

FIG. 7 is a right side isometric view of the cockpit seat tracks in the stowed position; and,

FIG. 8 is a top isometric view of the cockpit seat tracks.
